JOHAN S. FASTING, OF VALBY, NEAR COPENHAGEN, DENMARK, ASSIGNEE TO F. L. SMITH & CO., OF NEW YORK, N. Y., A CORPORATION OF NEW JERSEY

ROTARY KILN AND THE LIKE

Application filed September 19, 1929, Serial No. 393,614, and in Great Britain January 24, 1929.

In the operation of rotary kilns for the burning of slurry-like material, such as cement slurry in the manufacture of cement, the transfer of heat from the hot products of combustion to the slurry and the subsequent drying of the slurry, preliminary to calcination, in that portion of the kiln adjacent to the end at which the slurry is admitted, has been promoted by the suspension of a net 5 work of chains within the corresponding zone or portion of the kiln. In the rotation of the kiln such chains, heated during their passage through the space above the slurry, are immersed in the slurry during a part of 10 the rotation and give up their heat to the slurry. The slurry, which is a somewhat sticky mass, also adheres to the chains and is raised with the chains, as they emerge from the body of the slurry into the path of the 15 products of combustion. It has been found in the practical operation of rotary kilns equipped as heretofore with such chains the forward movement of the slurry from the inlet end of the kiln toward the outlet there- 20 25 of is retarded to an undesirable extent. It has, therefore, been the object of the present invention to provide for such arrangement of the chains in the kiln that, without diminishing their effectiveness in promoting the drying of the slurry, the forward movement of the slurry toward the outlet end of the kiln shall be promoted.

In accordance with the invention the chains are arranged in groups and the chains of each group are so arranged that as they emerge from the slurry, in their movement, they form a warped surface, the lower part of which, as it emerges from the slurry, slopes toward the outlet end of the kiln. Each such 30 35 40 45 50 warped surface raises a portion of the slurry from the mass at the bottom and its slope toward the outlet end of the kiln acts with something of the same effect which a solid scoop would have, urging the slurry forward toward the outlet end of the kiln. Incidentally, the chains which are so arranged will have, as they lie on the bottom of the kiln before they emerge from the slurry, a tendency to urge forward the whole mass of slurry. 50 Each group of chains acts independently of

every other group and does not interfere in any manner with the operation of any other group. The formation of the warped surface may be effected either by arranging the points of attachment of the chains as hereinafter described or by making the chains of each group of progressively increasing length toward the outlet end of the kiln, also as hereinafter described.

The invention will be more fully explained with reference to the accompanying drawing in which several embodiments of the invention are illustrated, necessarily in a somewhat schematic manner, and in which:

Figure 1 is a view in transverse section of a kiln equipped with chains of equal length in the improved arrangement, the plane of section being indicated by the broken line 1-1 of Figure 2.

Figure 2 is a view of a portion of the kiln, as seen from above, with three successive groups of chains in the described relation, the wall of the kiln being partly broken away and partly shown in section.

Figure 3 is a view similar to Figure 1 but illustrating, as far as may be necessary, the grouping together of three several groups of chains.

Figure 4 is a view similar to Figure 2, but illustrating the arrangement of chains shown in Figure 3.

Figure 5 is a view similar to Figures 1 and 2, but illustrating a different arrangement of the points of attachment of the chains to the kiln, with the chains progressively increasing in length toward the outlet end.

Figure 6 is a view similar to Figures 2 and 4, but showing the chains arranged as indicated in Figure 5.

Figure 7 is a view in side elevation, illustrating the arrangement of the chains as shown in Figures 5 and 6.

In Figures 1, 3 and 5 the arrow indicates the direction of rotation of the kiln and in Figures 2, 4, 6 and 7 the arrows in line with the axes of the kilns indicate direction toward the outlet end of the kiln.

In the embodiments of the invention illustrated in the drawing it is assumed that the chains are arranged in sets, each set com-

prising three groups, and that each group of chains is composed of five chains. It will be understood that the two ends of each chain of each group are secured by any suitable means to the inner face of the kiln wall and that the chains are slack between their points of attachment so that, in the rotation of the kiln, the chains take such positions as are indicated in the drawing. The several groups of chains may be secured to the kiln at points which are distributed longitudinally as well as peripherally, so that the chains have a roughly helical arrangement, as shown in Figure 2, or the several groups may be brought together in one general group with each chain lying in a substantially transverse plane, as shown in Figures 4, 6 and 7.

The several chains of each group may be of equal length, as represented in Figures 1, 2, 3 and 4, or they may be of unequal length, progressively longer toward the outlet end of the kiln, as represented in Figures 5, 6 and 7. If the chains of each group are of the same length the result desired is accomplished by securing the ends of the several chains of each group to the kiln at points which are distributed both in a peripheral direction and in a longitudinal direction with respect to the axis of the kiln. On the other hand, if the chains are of unequal length, being progressively longer toward the outlet end of the kiln, the chains of each group may be secured to the kiln in lines parallel with the axis and without peripheral distribution.

In the embodiment of the invention illustrated in Figures 1 and 2 the chains are shown as arranged in three groups *a*, *b* and *c* and the ends of the chains of each as secured to the kiln at points *d*, *e* and *f*. The five points of attachment in each group are distributed or displaced relatively to each other, not only in longitudinal direction, with respect to the axis of the kiln, but in a peripheral direction, as shown in Figure 2. The effect of this arrangement of the points of suspension of each group in a helical line is that the chains of each group, as at *a* and *b*, as they hang from the top, as shown in Figure 1, form a loosely hanging curtain or warped surface, between the points *e*, *f* and *e*, *d*, while the chains of the group *c* lie on the bottom of the kiln in lines, as indicated in Figure 2. When the kiln is rotated in the direction indicated by the arrow, Fig. 1, the chains of the group *b*, which have been immersed in the slurry and emerged from it, hang in such a position that the lower part of the warped surface, formed by the group of chains, slopes forward or toward the outlet end of the kiln, thus urging the slurry toward the outlet end of the kiln. The chains of the group *a*, which have emerged from the slurry and are again about to be immersed in the slurry, transferring

heat from the hot products of combustion above the slurry in the kiln to the slurry in the lower part of the kiln, also form a warped surface but with the lower part of such warped surface sloping in the opposite direction, that is, toward the inlet end of the kiln, but in this case the sloping part of the warped surface has no effect upon the movement of the slurry. The chains of the group *c*, passing through the slurry in the lower part of the kiln, have a tendency to arrange themselves along a roughly helical line and in the rotation of the kiln tend to sweep the slurry forward toward the outlet end of the kiln.

The embodiment of the invention illustrated in Figures 3 and 4 is substantially the same as that illustrated in Figures 1 and 2, except that the three groups *a*¹, *b*¹ and *c*¹ of the chains and their points of attachment *d*¹, *e*¹ and *f*¹ are brought together so that the chains of each group of the three several groups lie in peripheral lines, while the points of attachment of the chains of each group are distributed or displaced both longitudinally, with respect to the axis of the kiln, and peripherally, the chains of each group being of the same length.

It will be obvious that the formation of the loosely hanging curtain with a warped surface, which is necessary to urge the slurry forward in the kiln as each group rises from its lowest position to its highest position, may also be accomplished by securing the ends of the chains of each group *a*², *b*² and *c*², to the kiln at points, as at *e*², *d*² and *f*², which are distributed or displaced longitudinally, with respect to the axis of the kiln, as shown in Figures 5, 6 and 7, but in lines parallel with the axis of the kiln, the points not being distributed or displaced with respect to each other in a peripheral direction, but if the chains are thus arranged the chains of each group must be progressively longer toward the outlet end of the kiln in order that the chains may form a loosely hanging curtain with a warped surface, the lower portion of which slopes toward the outlet end of the kiln as each group rises from its lowest position.

In Figures 5, 6 and 7 the chains of each group are shown as lying in transverse planes, with several groups massed to form a general group.

It will be obvious that the chains may be secured to the kiln in any convenient manner and that they may be arranged in different ways to suit the conditions of operation, provided the formation of the loose curtain with a warped surface is accomplished. It will also be obvious that the invention may be applied to other purposes than the treatment of cement slurry.

I claim as my invention:

1. In an apparatus of the character described the combination of a rotating shell

and groups of slack chains secured at their ends to the interior of the shell, each group forming a loosely hung curtain with a warped surface, the lower part of which, as the group rises in the rotation of the shell, slopes toward the outlet end of the shell to urge the material in the shell toward the outlet end.

2. In an apparatus of the character described the combination of a rotating shell and groups of slack chains secured at their ends to the interior of the shell, the chains of each group being of the same length and the points of attachment of the chains of each group to the shell being distributed in a longitudinal direction with respect to the axis of the shell and in a peripheral direction, each group forming a loosely hung curtain with a warped surface, the lower part of which, as the group rises in the rotation of the shell, slopes toward the outlet end of the shell to urge the material in the shell toward the outlet end.

This application signed this 31st day of August A. D. 1929.
